UNITED STATES PATENT OFFICE.

EDGAR W. TAIT, OF BRADFORD, PENNSYLVANIA.

ART OR METHOD OF MAKING GASOLENE.

1,069,908.

Specification of Letters Patent. Patented Aug. 12, 1913.

Application filed March 20, 1911. Serial No. 615,727.

To all whom it may concern:

Be it known that I, EDGAR W. TAIT, citizen of the United States of America, residing at Bradford, Pennsylvania, have 5 invented certain new and useful Improvements in the Art or Method of Making Gasolene, of which the following is a specification.

My invention consists of certain new and 10 useful improvements in the art or method of making gasoline.

My process consists in exposing to applied heat natural gas commingled with a higher liquid paraffin, the heat vaporizing 15 the higher liquid paraffin, and then condensing the resultant to form a liquid of lower specific gravity than that of the higher liquid paraffin.

In carrying out my process I commingle 20 kerosene, naphtha or other of the higher paraffins, in either a liquid or a gaseous form, with either hot or cold natural gas, and then heat them together in either a tank, still, or long worm or coil of pipe by 25 means of an exterior flame or burner, the heat vaporizing the higher paraffin. The natural gas may be introduced into this tank, still, or worm or coil of pipe, either at the natural rock pressure from the well, 30 or it may be forced therein by means of a pump or compressor. The degree of heat to be applied varies from about 200° Fahrenheit upward, depending on the quality of the natural gas used, the specific gravity of 35 the higher paraffin used, and on the desired specific gravity of the product. The relative amount of the higher paraffins to the volume of natural gas used depends on the desired specific gravity of the product; (for 40 instance, if the quantity of the kerosene, naphtha or other higher paraffins in proportion to the quantity of the natural gas used is diminished, the product becomes of lower specific gravity). I then condense the com- 45 mingled vaporized hydrocarbons into a liquid to form a hydrocarbon liquid suitable for use in explosive engines. The condensation may be effected by any known method,—preferably by passing the com- 50 mingled vaporized hydrocarbons through a long worm or coil of pipe until the mass is sufficiently cooled, and then into a separator. Additional cooling may be had by expanding the unconsumed gas in the tank,

into a tank or pipe incasing the coil or worm 55 in which the commingled vaporized hydrocarbons are traveling.

I have illustrated in the accompanying drawing, which is a diagrammatic view, one means of carrying out my process. 60

In this drawing, A represents the gas inlet from the well, and if the natural pressure is not sufficient to give a free circulation through the system, I use a compressor B operated by an engine C which also actuates 65 a pump D in connection with an oil tank E. The gas preferably flows or is forced through a pipe F, and in its passage is subjected to the heat of a burner G, and after it issues from the action of the burner it is 70 commingled with oil or naphtha passing through the pipe H. From this point the commingled hydrocarbons pass through a pipe which is under the action of a second 75 burner I, and thence pass through the condenser or cooling system, whence the hydrocarbon liquid suitable for use in explosive engines passes into the receiving tank.

A typical instance of the operation of my process is as follows:—If there is not sufficient natural pressure from the gas well, compressor B should compress the natural gas taken into the system to a pressure of about 50 pounds per square inch, sufficient to cause a free circulation through the system. 80 The natural gas travels through the coil G at the rate of 5,000 cubic feet per hour. The coil or worm G is composed of a pipe two inches in diameter and about 200 feet in length. In the coil or worm G the 85 natural gas is heated to about 500° F. The oil or higher paraffin is pumped into the natural gas at the rate of about 60 gallons per hour. The coil or worm I is composed 90 of a pipe two inches in diameter and about 300 feet in length. The temperature of the commingled substances in the coil I is maintained by means of the burner shown at 95 about 300° F. The cooling system is composed of a pipe two inches in diameter and about 1000 feet in length, of which the last two hundred feet are incased or jacketed. The pop valve on the receiving tank releases 100 the unconsumed gas when the pressure in the receiving tank reaches 50 pounds per square inch.

I do not limit myself to the above dimensions or quantities. Better results are ob-

tained by using natural gas containing a high percentage of ethane or higher paraffins.

What I claim and desire to secure by 5 Letters Patent is:—

1. The process of forming a hydrocarbon liquid suitable for use in explosive engines by commingling natural gas in proper proportion with a higher liquid paraffin and 10 exposing them to applied heat, the heat vaporizing the higher liquid paraffin, and then condensing the resultant to form a liquid of lower specific gravity than that of the higher liquid paraffin.
- 15 2. The process of forming a hydrocarbon

liquid suitable for use in explosive engines by commingling heated natural gas in proper proportion with a higher liquid paraffin and exposing them to applied heat, the heat vaporizing the higher liquid paraffin, 20 and then condensing the resultant to form a liquid of lower specific gravity than that of the higher liquid paraffin.

In testimony whereof, I affix my signature in presence of two witnesses.

EDGAR W. TAIT.
